United States Patent Office.

SOCRATES SCHOLFIELD, OF PROVIDENCE, RHODE ISLAND.

Letters Patent No. 97,818, dated December 14, 1869.

IMPROVEMENT IN TWIST-DRILLS.

The Schedule referred to in these Letters Patent and making part of the same.

To all whom it may concern:

Be it known that I, SOCRATES SCHOLFIELD, of Providence, in the county of Providence, and State of Rhode Island, have invented an Improvement in Drills; and do hereby declare that the following is a full and exact description, reference being had to the accompanying drawings, making a part of this specification.

The nature of my invention consists in the use of certain guiding-lines or grooves upon twist or other similar drills, as a permanent guide to the workman, whereby they may be ground properly.

To enable those skilled in the art to make and use my invention, I will proceed to describe its construction and operation.

Figure 1 represents a side view, and

Figure 2, an end view, showing the position of the lines contemplated.

In the matter of grinding a common twist-drill, it is very essential that the proper centre be preserved, so that it may always drill a hole of the same size. In order that this end may be secured, I trace the lines *a a* and *a' a'*, longitudinally at the bottom of each groove, which lines are to constitute a working-gauge for the length of each cutting-lip, and should be drawn on opposite sides, a little out of the centre of the drill, so that the centre penetrating-edge *a a'* may run diagonally from the bottom of one groove to the other, as shown in fig. 2.

It will be readily perceived that if the lines *a a* and *a' a'*, were drawn in the exact centre, and opposite each other, the proper angle for grinding each lip of the drill could not well be preserved, since a diagonal edge, *a a'*, is the result of the intersection of the two inclined surfaces of the end of the drill, when properly ground.

On the outer surface of the drill may be traced the parallel lines *b b* and *b' b'*, in order to furnish a gauge whereby the proper angle of the cutting-edge may be preserved, since the distance to the nearest line *b* and *b'* may be easily estimated by the eye, and made the same in both.

Thus, by starting at the diagonal centre-line *a a'*, and reaching a point on each lip at the same distance from its nearest outside line, the proper centre and angle may be easily determined by inspection.

The lines *b b* and *b' b'*, may be traced about a quarter of an inch apart upon the surface of the drill,

either directly around the drill, or in the form of a double screw-thread, which will also give corresponding lines on opposite sides of the drill.

The mode of putting on the lines *a a* and *a' a'*, may be varied. I prefer the use of a diamond in making a scratch or groove, to indicate the proper lines, the point of the diamond being pressed to the groove of the drill by a spring or weight, so as to produce a uniform cut throughout, as the drill is being turned and drawn backward.

This centre line or groove may be made of any desired width, one edge being taken, when very wide, as the proper location of the inner corner of the cutting-lips.

These lines may also be etched by means of an acid-bath, after being traced on a waxed surface by suitable mechanism, or they may be merely stained upon the surface of the steel by the use of proper chemicals, the necessary requirement being permanence, and that they should present on the side toward the cutting-lip a smooth and well-defined edge.

I am aware, that in the extensive manufacture of twist-drills, as a specialty, a certain milling-tool has been used for roughing out, which leaves a faint sort of line in its track at the centre of the drill, but such line has been produced without reference to the proper position of the inner corner of the lip, and has invariably been either obliterated by another cutter, or filed out, so as not to appear on the finished drill; therefore I do not claim such accidental line, made during the primary stage of the drill's manufacture, when, as heretofore, not retained as of use in the finished drill, for the purpose specified; but

What I claim as my invention, and desire to secure by Letters Patent, is—

A twist, or other similar drill, marked with distinct centre-guiding lines or grooves *a a* and *a' a'*, for the purpose of indicating the proper position of the inner corner of each lip in grinding.

Also, the combination of the parallel exterior lines *b b* and *b' b'*, with the centre-guiding lines *a a* and *a' a'*, substantially as described.

SOCRATES SCHOLFIELD.
